OF OHIO.

ATTACHMENT-PLUG FOR ELECTRIC CIRCUITS.

1,080,326.

Specification of Letters Patent.

Patented Dec. 2, 1913.

Application filed February 24, 1913. Serial No. 750,300.

To all whom it may concern:

Be it known that we, FRANK H. CHAPMAN and OWEN E. KENNEY, citizens of the United States, and residents of Toledo, in the county of Lucas and State of Ohio, have invented a certain new and useful Attachment-Plug for Electric Circuits; and we do hereby declare the following to be a full, clear, and exact description of the invention, such as will enable others skilled in the art to which it appertains to make and use the same, reference being had to the accompanying drawings, and to the characters of reference marked thereon, which form a part of this specification.

This invention relates to coupling devices for electric circuits and particularly to the plug and socket type of coupling of the quick connecting class, but is not limited to such use, as it may be employed in any connection for which it may be adapted or appropriate.

The object of our invention is the provision of an improved plug member for couplings of this character, which is simple and inexpensive of manufacture, composed of a minimum of parts, is capable of being easily and quickly connected to circuit wires and also of being quickly coupled to a socket member, whereby to enhance the practicability and commercial value thereof.

The invention is fully described in the following specification, and while in its broader aspect it is capable of embodiment in numerous forms, a preferred embodiment thereof is illustrated in the accompanying drawings, in which,

Figure 1 is an enlarged central longitudinal section of a portion of the socket member and of the plug member embodying the invention with the latter partly inserted into the former, and Figs. 2 and 3 are enlarged side and inner end elevations of the plug member.

Referring to the drawings, A designates the socket member of the coupling, which member is of customary or any suitable construction, and has the central contact part 1 and the spirally grooved or threaded lining 2 forming the other contact of the socket.

The plug member B of the coupling, in

which the features of our invention reside, comprises the body part 3 and the plunger 4, both of insulating material, with the latter mounted for axial or longitudinal reciprocatory movements in a socket 5 in one end of the body part 3. A coiled compression spring 6 is interposed between the base of the socket 5 and the inner end of the plunger 4 and acts on the plunger to influence an outward movement thereof and to normally maintain its outer end projected a short distance without the open end of the socket 5, such distance of projection being limited as hereinafter described.

The side wall of the plug socket 5 is provided with a longitudinally-extending slot or opening 7, which preferably opens without the outer end of such wall. The outer side of this slot is closed by a suitable electrical conductor, which, in the present instance, is in the form of a sleeve or ferrule 8 that is fitted closely around the socketed end of the plug body part 3. This sleeve or ferrule forms an annular contact surface for engagement with the lining 2 of the socket member when inserted therein, as shown in Fig. 1. The outer end of this sleeve or ferrule 8 is preferably flanged or turned inward over the adjacent end edge of the plug part 3, as shown at 9.

The plunger 4 is provided in one side thereof from adjacent to its inner end with a recess or channel 10 in which a longitudinally extending conductor strip 11, preferably of spring metal, is mounted, being secured therein by the clamping action of a bar 12 and screw 13, which latter is threaded into the plunger. The end portion of the conductor strip 11, which is disposed adjacent to the outer end of the plunger, is bent outwardly to provide a spring finger or brush 14, which is adapted to project at its outer end into the slot or opening 7 in yielding sliding contact with the portion of the ferrule 8 which closes the outer side of such slot. The finger 14 normally engages the inturned flange 9 at the outer end of the ferrule to limit the outward movements of the plunger 4 relative to the plug part 3 under the influence of the spring 6. The slot 7 is of sufficient length to permit the

finger 14 to remain in contact with the ferrule 8 during the complete inward compressing movements of the plunger 4 within the part 3. The spring finger 14 in addition to coacting with the ferrule 8 to close the electrical connection therebetween, and coacting with the ferrule flange 9 to limit the outward movements of the plunger relative to the plug part 3; also coacts with the side walls of the slot 7 in the part 2 to guide the reciprocatory movements of the plunger within the part 3.

The plunger 4 is provided at its outer end with a centrally disposed contact part 15 for engagement with the socket contact part 1 when the plug is inserted into the socket member. The lead-in wires for the plug are intended to enter the socket 5 of the plug part 3 through a central opening 16 in the end thereof opposed to that in which the socket is provided, and one wire, in the present instance, is clamped to the bar 12 by a binding-screw 17, while the other wire extends through the plug and is attached to the contact part 15 by a binding-screw, or in any other suitable manner.

The means employed, in the present instance, for securing the coupling members A and B together, when inserted one within the other, comprises a ball or locking part 18, which is mounted in a cage 19 within the socket wall of the part 3 and is adapted to be forced outward into locking engagement with a registering groove in the socket lining 2 when the plunger is depressed into the part 3 upon an insertion of the plug into the socket member. The part 18, when in its retracted position, works in a longitudinal groove or channel 20 in the plunger 4 and is forced outward by the contact therewith of a hardened thrust part 21, which is set into the plunger at the outer end of the groove 20 in position to engage the part 18 when the plunger has been depressed a predetermined extent within the part 3. While the part 18 may be cammed or forced out in any other suitable manner it is preferable to provide the plunger with a hardened thrust part 21 for such purpose.

The ferrule 8 is provided with a small opening 22 in register with the outer end portion of the slot 7 to enable a pin or other pointed instrument to be inserted therein to effect a depression of the spring finger 14 from stop engagement with the ferrule flange 8 to permit an outward movement of the plunger from within the socket 5 when desired. It will be noted that the sleeve or ferrule 8 is spaced from the metal ball retaining cage 19, as at 23, to insulate the locking means from the line circuit.

It is evident that our improved plug is exceedingly simple and inexpensive in construction, and adapted to have the parts thereof easily and quickly assembled; and

also materially facilitates the attaching of circuit wires thereto. It is also evident that the spring finger or brush 14 has a three-fold function, namely, to guide the reciprocatory movements of the plunger 4 within the plug part 3, to coöperate with the flange 8 or other suitable stationary part at the outer end portion of the slot 7 to restrict the outward projecting movements of the plunger 4 relative to the part 3, and to have sliding electrical contact with the ferrule 8 whereby the circuit may pass from such ferrule to the socket lining 2, or vice versa, when the plug member is inserted into the socket member.

We wish it understood that our invention is not limited to any specific arrangement, construction or form of the parts except in so far as such limitations are specified in the claims.

Having thus described our invention, what we claim as new, and desire to secure by Letters Patent, is—

1. A plug of the class described having two sections mounted for limited relative longitudinal movements one within the other, means influencing a relative outward movement of said sections, a conductor part carried by each section with the conductor part of the outer section in exposed position on a side thereof, and a spring brush conductor member connecting said parts and having sliding contact with one of them when the sections are relatively moved.

2. A plug of the class described having two telescoping sections mounted for limited relative axial movements, means influencing a relative movement of the sections in one direction, a conductor part fixedly carried at the outer side of the outer section, a conductor part attached to the inner section, and a spring conductor member connected to one of said conductor parts and having permanent sliding contact with the other of said parts when the sections are assembled.

3. A plug of the class described comprising a body section having a hollow extension at one end, a contact member fixedly carried in externally exposed position by said extension and having an internally exposed part, a plunger mounted for limited reciprocatory movements within said extension, means influencing an outward movement of the plunger relative to the extension, a conductor member carried by the plunger, and a yieldable conductor element connected to one of said members and having sliding contact with the other.

4. A plug of the class described comprising a body section of insulating material provided in one end with a longitudinal socket the wall of which socket is provided with an opening, a conductor part fixedly carried in externally exposed position by said wall and having a portion exposed to

the interior of the socket through said opening, a plunger mounted for limited longitudinal reciprocatory movements in said socket, a conductor part carried by the plunger, and a spring brush member projecting from one of said conductor parts through said opening and having sliding contact with the other part when the section and plunger are relatively moved.

10 5. A plug of the class described having a pair of telescoping sections mounted for relative reciprocatory movements, means influencing a relative outward movement of said sections, conductor members respectively carried by said sections, and means coacting with one of said members to limit the relative outward movements of the sections.

20 6. A plug of the class described having a pair of relatively movable telescoping members each having a contact part, means influencing a relative outward movement of said members and means on one of said contact parts for coacting with the contact part 25 of the other member to limit the relative outward movements of said members.

30 7. A plug of the class described having a member provided with a socket having an opening in its wall, a conductor part carried by said member and having at least a portion thereof exposed to the interior of the socket through said opening, a plunger reciprocally movable in said member socket, and a conductor part carried by said plunger 35 for movements therewith and extending into said opening and being in sliding contact with the conductor part of said member.

40 8. A plug of the class described having a socketed member, a plunger reciprocally movable in said member, a yielding brush part carried by said plunger and having sliding electrical contact with said member, and means coöperating with the brush part to guide and limit the relative movements 45 between said member and plunger.

50 9. A plug of the class described having a socketed member, a plunger reciprocally movable in said member, a contact sleeve encircling the socket portion of said member and having a portion exposed to the interior thereof, and a conductor part carried by the plunger for movements therewith and having sliding contact with the portion of said sleeve exposed to the interior of said member.

55 10. In a plug of the class described, a member provided with a socket having a recess in its wall, an external contact part carried by said member over said recess, a plunger mounted in said member, means for influencing an outward movement of said plunger relative to said member, and a spring conductor finger carried by said plunger for movement therewith and projecting into said recess in sliding contact with said 60 external contact part and adapted to coact

with the wall of said recess to limit the outward movements of the plunger relative to said member.

11. A plug of the class described having telescoping sections mounted for relative longitudinal movements, means influencing a relative outward movement of said sections, and coacting releasable catch parts on said members one at least forming a part of an electric circuit and operating to limit the 75 relative outward movements of said members.

12. A plug of the class described having a socketed body member provided with an opening in its socket wall, a contact part carried by said member and closing the outer side of said opening, a plunger reciprocally movable in the socket of said member, a yielding conductor part carried by said plunger for movements therewith and having its 80 free end projecting into said opening in sliding contact with said contact part, means carried by said member for coacting with said conductor part to limit the relative outward movements of said member and plunger, said contact part having an opening in register with the socket member opening for the insertion of an instrument to depress said conductor part to release its engagement with said means.

95 13. In combination, a socket member having base and lining contacts therein, a plug having relatively movable telescoping sections, the outer of said sections having an external contact part for engagement with the lining contact of said socket member, and the inner of said sections having a contact part for engagement with the base contact of said socket member and also a contact part in yielding sliding engagement 100 with said external contact part, and means carried by the plug and operable by a predetermined relative movement of the sections thereof to engage the lining of the socket member to retain the plug and socket member in assembled relation when the former has been inserted a predetermined extent into the latter.

105 14. A plug of the class described having a pair of relatively movable telescoping members, a contact part carried by each member, one in sliding contact with the other, and means coacting with one of said parts to prevent a relative rotation of the members.

115 15. In combination, a socket member having a lining forming an electrical contact part, a plug for fitting into said member and having two telescoping sections mounted for relative longitudinal movements, a contact part carried by each of said sections in sliding contact one with the other and the contact part of the outer section having contact with the contact part of the socket member when inserted therein, and means 125 130

separate from said contact parts and oper-
able by a predetermined relative movement
of the plug sections to engage the socket
member lining to retain the plug and socket
5 member in assembled relation when the for-
mer has been inserted a predetermined ex-
tent into the latter.

In testimony whereof, we have hereunto

signed our names to this specification in the
presence of two subscribing witnesses.
